Primary Examiner — Patricia A Palasik*(74) Attorney, Agent, or Firm* — Peter J. Ims; Westman, Champin & Koehler, P.A.(57) **CLAIM**

The ornamental design for a nozzle, as shown and described.

DESCRIPTION

FIG. 1 is a top perspective view of a nozzle;
FIG. 2 is a bottom perspective view of FIG. 1;
FIG. 3 is a side elevational view of FIG. 1, the opposing side, the front and the rear being identical;
FIG. 4 is a bottom plan view of FIG. 1;
FIG. 5 is a top plan view of FIG. 1; and,
FIG. 6 is an enlarged sectional view taken along line 6-6 in FIG. 3.

The broken lines shown in the drawings are included for purposes of illustrating portions of the nozzle and form no part of the claimed design.
